UNITED STATES PATENT OFFICE.

DAVID B. BOGARD AND ELMER BEASLEY, OF CARTERVILLE, ILLINOIS.

TOP-BUGGY.

No. 866,569.

Specification of Letters Patent.

Patented Sept. 17, 1907.

Application filed April 26, 1907. Serial No. 370,448.

To all whom it may concern:

Be it known that we, DAVID B. BOGARD and ELMER BEASLEY, citizens of the United States, residing at Carterville, in the county of Williamson and State of Illinois, have invented certain new and useful Improvements in Top-Buggies, of which the following is a specification, reference being had therein to the accompanying drawing.

The invention pertains particularly to buggies, and 10 the like, and the object thereof, is to provide a buggy-top having improved means, by which it may be detached from the body of a vehicle.

The invention aims principally to provide a device of this character, which is simple in construction, durable in practice and inexpensive in production.

With these and other objects in view, the invention comprises further combinations of features and elements, which will be hereinafter described, pointed out in the appended claims, and illustrated in the accompanying drawings, wherein

Figure 1 is a perspective view, of the device showing a portion of a buggy-top connected thereto. Fig. 2 is a perspective view of the device detached. Fig. 3 is a sectional view on line 3—3 of Fig. 1.

Referring particularly to the accompanying drawings, 1 designates the side of a buggy seat, to which is bolted, a pair of angle members 2; there being a pair on each side of the buggy seat, but only one pair being shown. These angle members are apertured as shown 20 at 3, in Fig. 3, which apertures receive the lugs 4 carried integrally by the side rail 5 of the buggy top, as

clearly shown in Fig. 1. This side rail supports the angularly disposed stays 6 of the buggy-top as shown at 7. The said lugs, carried by the side rails, are slotted as shown at 8, which receive, after the lugs are inserted 35 through the apertures of the angle members, the lateral projecting lugs 9, integrally carried by the latch levers 10, which are pivoted to the said side rail, as clearly shown in Fig. 1, the said latch levers are provided with thumb pieces 11, adjacent to the lugs received by the 40 slots of the lugs carried by the said rails.

From the foregoing description, in connection with the drawings, it will be plainly observed that a very efficient device is provided, which is designed to be carried by buggy-tops, and by which, the said top may 45 be readily removed and replaced, when desired.

Having thus described the invention, what is claimed as new and useful is,

In a device as set forth, a vehicle seat, plates secured thereto, said plates having horizontally disposed portions 50 projecting therefrom, said horizontal portion having openings, a side rail having downwardly projecting lugs to engage said openings, said lugs having slots therein, a pair of latch levers having downwardly projecting portions provided with lateral projecting lugs pivoted approximately to the center of the said side rail, said lateral projecting lugs are adapted to engage said slots as specified.

In testimony whereof we hereunto affix our signatures in presence of two witnesses.

DAVID B. BOGARD.
ELMER BEASLEY.
